RUGGEDIZED KLYSTRON TUBE

Wilbur A. Joerndt, Silver Spring, Md., assignor
to the United States of America as represented
by the Secretary of the Navy

Application September 15, 1950, Serial No. 184,939

5 Claims. (Cl. 315—5)

1

The present invention relates to improvements in electron tubes of the velocity modulated cavity resonator type, commonly known as Klystrons.

When Klystrons are incorporated in the guidance systems of guided missiles, they are subjected to shocks and vibrations not contemplated in the ordinary uses for which such tubes were designed, and as a result they are usually damaged to such extent that in even the less serious cases their frequency of oscillation is materially changed, rendering them useless.

One of the principal objects of the present invention, therefore, is to provide a Klystron which will be of extremely rugged construction so that it will be capable of withstanding without damage to its operating efficiency the severe shocks and vibrations existing in a guided missile under acceleration.

Another object of the invention is to provide, in a Klystron, highly efficient cavity resonator tuning means which will remain in adjustment even under the most severe operating conditions.

A further object is to provide an extremely rugged Klystron oscillator tube, the cavity resonator of which may be tuned by a single adjusting means.

Still another object of the invention is to provide a Klystron oscillator tube having, in one embodiment, effective means for cooling.

Other objects and many of the attendant advantages of this invention will be appreciated readily as the same becomes understood by reference to the following detailed description, when considered in connection with the accompanying drawings, wherein:

Fig. 1 is an elevation of the improved Klystron; Fig. 2 is a plan thereof;

Fig. 3 is an elevation, partly broken away and in section in the plane 3—3 of Fig. 2;

Fig. 4 is a fragmentary elevation, partly in section in the plane 4—4 of Fig. 2, showing the cavity resonator tuning structure; and

Fig. 5 is an elevation, partly broken away and in section, of a modified form of the invention.

Referring to Figs. 1—4 inclusive, and first more particularly to Fig. 3, some of the structure of a conventional Klystron is shown.

The Klystron comprises a base 1 carrying a metal envelope 2 which is evacuated and contains the heater and electrodes. This envelope 2 has a lower cylindrical wall 3 of relatively large diameter surmounted by a wall 4 of smaller diameter and an uppermost portion or circular head 5 of intermediate diameter. A flat radial flange 6 connects walls 3 and 4, and provides a certain degree of flexibility so that walls 3 and 4 can move longitudinally with respect to each other to a limited extent.

An inner partition 7, shown as a continuation of wall 3 at the junction of flange 6 and wall 3,

2

remains substantially stationary when flange 6 is flexed. A smoothing grid 9 is carried by a diaphragm 8 secured to wall 4, and a second smoothing grid 10 is located in a central opening of partition 7, said parts thus defining a cavity resonator 11. When the wall 4 is forced downward, it carries along the diaphragm 8 and screen 9, toward the stationary partition 7 and screen 10, thus diminishing the size of the cavity.

In carrying the present invention in effect, there is provided a jacket 12, shown in section in Fig. 3 and in elevation in Fig. 1. This jacket 12 is made of rigid metal, such as steel and is secured firmly and intimately to the envelope 2, as by "sweated" solder. The jacket 12 has at its upper end a portion 14 of reduced diameter, and at the upper end of said portion 14 the said jacket carries an outwardly extending flange 15 which constitutes a support. This flange 15 provides mounting means for the cavity resonator tuning mechanism which will now be described.

The cavity tuning mechanism comprises a movable top plate 16 which is firmly secured to the top portion 5 of the envelope 2, as by sweating soldering it around said portion. At its forward end 17, as shown in Figs. 1 and 3, the plate 16 has holes to receive screws 18 whose lower ends are threaded into an adjacent projection 19 of the flange 15. Shims 20 may be placed between elements 17 and 19 to space the plate and flange a desired distance apart. As best seen in Figs. 2 and 4, the plate 16 terminates at its rear end in spaced lugs 21 which straddle a link 22 to which they are hingedly attached by a pin 23.

The lower end of the link 22 is received between a pair of spaced lugs 24, 25, Fig. 4, extending rearwardly from flange 15, and is connected to said lugs by a pin 26. This pin has a head 27 fitting rotatably in a bore in lug 25 and is secured against axial movement by a pin 28 passing through said lug and engaging in a circumferential groove 29 formed in said head. An intermediate portion 30 of the pin 26, of smaller diameter than the head 27, fits rotatably in a corresponding bore in the link 22, but is not coaxial with the head 27, being intentionally made with a slight amount of eccentricity, so that rotation of pin 26 will move the link 22 up or down for moving plate 16 and tuning the cavity 11. Thus the pin 26, having the cylindrical portion 30 non-coaxial with the cylindrical portions 27 and 31, constitutes a crank for moving the link 22. The pin 26 has a further portion 31 of still smaller diameter, and coaxial with the head 27. This portion 31 is mounted for rotation in bushing 32 having tapered threads 33 engaging in a correspondingly tapered threaded bore in lug 24, said bushing being slotted so that its inner end may contract and grip the portion 31 when the said bushing 32 is screwed into place, thus normally

locking the pin 26 against rotation. A squared end 34 is provided on portion 31 for engagement by a suitable key or wrench when the pin 26 is to be turned. Pin 26 may also be turned by a screw driver, engaged in its head 27, which is slotted for the purpose. Bushing 32 may be gripped by pliers or turned by means of the slot 32a in its head.

The modified form shown in Fig. 5 is substantially the same as the form shown in Figs. 1-4, except that it is provided with cooling fins 35 on its jacket 12a, as well as ventilating holes 36 in the portion 14a of said jacket. To increase the cooling effect, the jacket 12a may be made of brass or other metal of good head conductivity.

The operation of the device may be summarized briefly as follows:

The jacket 12 is of sufficient thickness to prevent distortion of the tube envelope under severe shocks and vibration. The continuation 14 of said jacket provides a rigid support for the flange 15, which in turn supports the upper plate 16, secured to the head 5 of the Klystron.

At the forward end 17 of this plate, the shims 20 provide a rigid abutment between elements 17 and 19, and such shims may be provided after the desired cavity resonator tuning adjustment has been found by experiment. At the rear end the link 22 constitutes a rigid positioning device, and stays in its adjusted position when the bushing 32 is tightened.

Since the head 5 is thus adjusted up or down by turning the pin 26, it is clear that any desired adjustment of the cavity resonator 11 may be secured, and that said cavity resonator adjustment will be effectively maintained even when the tube is subjected to severe shocks and vibration.

The form shown in Fig. 5 may be used where it is desirable to limit the heat, inasmuch as the openings 36 and heat dissipating fins 35 will make it possible to operate the tube at lower temperatures than the form of Figs. 1-4.

An advantage of both forms of the invention is that both the squared end 34 of the pin 26 and the bushing 32 are so located that they may readily be reached and manipulated by suitable tools, such as socket wrenches, screw drivers, or special combination tools designed for the purpose, if preferred, even after the Klystron is assembled in a missile or the like, thus making final adjustments relatively easy, while at the same time assuring ample rigidity to prevent derangement of said adjustments.

Obviously many modifications and variations of the present invention are possible in the light of the above teachings. It is therefore to be understood that within the scope of the appended claims the invention may be practiced otherwise than as specifically described.

What is claimed is:

1. A cavity resonator having conducting walls, a jacket surrounding the conducting walls and having a flange, a plate mounted above the flange and connected to certain of the conducting walls of the cavity resonator, certain other of said conducting walls being connected to said flange, and tuning means for the cavity resonator connected to said plate and said flange and comprising a pin in the flange and having an eccentric portion, said pin and eccentric portion being movable for shifting the plate with respect to the flange.

2. A cavity resonator having means for varying the size of the cavity resonator for electrically tuning the same, said means including a jacket, a plate adjustably mounted on the jacket and connected with the cavity resonator, and eccentric means for shifting the plate with respect to the jacket, said eccentric means including a crank having two non-coaxial cylindrical portions, one of said portions being journaled in the jacket and a link hinged at one end to the plate and pivoted at its other end on the other cylindrical portion whereby the plate may be adjusted with respect to the jacket by turning said eccentric means.

3. An electron discharge device comprising an envelope and a tunable cavity resonator, a sleeve surrounding the envelope and cavity resonator and having a flange at one end, a plate mounted in spaced relation above the flange, means connecting one side of the plate rigidly to the flange, said plate and flange being connected to the cavity resonator, a link connecting the flange with the other side of the plate, means pivotally connecting one end of the link with the plate, and means connecting the other end of the link with the flange, said last-mentioned means comprising a pin having an eccentric portion, said pin and eccentric portion being rotatable for shifting one side of the plate with respect to the flange for changing the shape of the cavity resonator for tuning the same.

4. An electron discharge device comprising an envelope including a lower wall of relatively large diameter surmounted by a wall of smaller diameter, said walls defining a flexible radial flange, a diaphragm cooperating with said walls and flange defining a cavity resonator, a sleeve surrounding the envelope and having a flange, said sleeve being rigid and being firmly secured to the envelope to stiffen and reinforce said envelope, a plate spaced above the flange, means rigidly connecting one side of the plate to the flange, a wall of intermediate diameter formed on the envelope and fitted to said plate, said last-named wall being rigidly secured to the plate and eccentric means carried by the flange and adjustable for shifting the other side of the plate whereby the walls defining the cavity resonator will be shifted for tuning said resonator.

5. A cavity resonator having conducting walls, means for varying the size of said cavity resonator, comprising, spaced rigid members engaging certain of said conducting walls and means including a rotatable crank having two non-axial cylindrical journal portions coupled to said respective rigid members, for varying the spacing of said members and thus shifting said walls to vary the size of the cavity.
